CLAIM

The ornamental design for a wallet, as shown and described.

DESCRIPTION

FIG. 1 is a first perspective view of the wallet.

FIG. 2 is a second perspective view thereof.

FIG. 3 is a top view thereof.

FIG. 4 is a bottom view thereof.

FIG. 5 is a first side view thereof.

FIG. 6 is a second view thereof.

FIG. 7 is a back view thereof; and,

FIG. 8 is a front view thereof.

The long dash broken lines in FIG. 1 depict environment and does not form part of the claimed design. The short dash broken lines depict portions of the wallet and form no part of the claimed design.

1 Claim, 6 Drawing Sheets(56)
